Fig. 8

Fig. 10

FIG. 1 is a perspective view of a three-level curved shelf unit showing my new design;

FIG. 2 is a top plan view of the three-level shelf unit;

FIG. 3 is a front elevational view of the three-level shelf unit;

FIG. 4 is a left side elevational view of the three-level shelf unit taken along line 4-4 of FIG. 2;

FIG. 5 is a bottom plan view of the three-level shelf unit;

FIG. 6 is a perspective view of a five-level curved shelf unit showing another embodiment of my new design;

FIG. 7 is a top plan view of the five-level shelf unit;

FIG. 8 is a front elevational view of the five-level shelf unit;

FIG. 9 is a left side elevational view of the five-level shelf unit taken along line 9-9 of FIG. 7; and

FIG. 10 is a bottom plan of the five-level shelf unit.

I claim:

The ornamental design for a curved shelf unit, as shown.
